UNITED STATES PATENT OFFICE.

OSCAR WIENER, OF NEWARK, NEW JERSEY.

DESIGN FOR SADDLE-HOOKS FOR HARNESS.

Specification forming part of Design No. 5,208, dated August 15, 1871.

To all whom it may concern:

Be it known that I, OSCAR WIENER, of Newark, New Jersey, have invented and produced a new and original Design for Saddle-Hooks for Harness, of which the following is a specification:

A represents the portion of the saddle-hook extending out from the saddle, and terminating in a knob, *a*. B is a curved arm extending down

from the portion A, and terminating in a knob, *b*.

What I claim is—

The design for saddle-hook, consisting of the portion A and arm B, as herein shown and described.

OSCAR WIENER.
